INVENTOR
Frederick M. Furber
By his Attorney,
Robert W. Howard

UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

MECHANISM OR APPARATUS FOR HOLDING OR TRANSFERRING ARTICLES.

Application filed December 21, 1918. Serial No. 267,784.

To all whom it may concern:

Be it known that I, FREDERICK M. FURBER, a citizen of the United States, residing at Revere, in the county of Suffolk and State of 5 Massachusetts, have invented certain Improvements in Mechanism or Apparatus for Holding or Transferring Articles, of which the following description, in connection with the accompanying drawings, is a specification, like reference characters on the drawings indicating like parts in the several 10 figures.

This invention relates to mechanism or apparatus for holding or transferring articles and is particularly designed for use in the manufacture of shoes for picking up pieces of material one at a time and delivering them in proper relation to other parts of a shoe in process of manufacture. As 15 hereinafter specifically described by way of illustration, the invention is embodied in a type of picker in which the article or blank to be transferred is penetrated by a plurality of spurs which are movable relative 20 to each other in order operatively to engage or to release the article. However, it will be apparent that the invention in its broader aspects, and even the particular form of mechanism shown, is capable of wide application. 25

The primary object of the invention is to produce a novel mechanism of the character above indicated which will be simple, efficient and reliable both in construction and 30 in mode of operation. With this and other objects particularly in view, the invention comprises certain combinations and arrangements of parts as well as various details of construction, which will now be described 35 in connection with the accompanying drawings and the scope of which will then be defined in the appended claims.

In the drawings,

Fig. 1 is a side elevation, partly in section, of a picker constituting a preferred embodiment of the invention;

Fig. 2 is a similar view of the picker in a different position and with the ejecting foot omitted;

Fig. 3 is an end elevation of the picker constructed as shown in Fig. 2;

Fig. 4 is a sectional plan along the line of IV-IV of Fig. 3, and

Fig. 5 is a detail in perspective of one of the spurs.

55

The mechanism illustrated has been particularly designed for use as an element in a machine which applicant has invented for transferring soles, sheet filler material, etc., in the manufacture of shoes. The mechanism, however, may obviously be embodied in a simple tool supported and operated in the hand.

As illustrated, the picker is intended to engage a sole, such as that designated 2, at 65 the top of a stack 4, to remove the sole and deliver it at any desired location, as for example on the bottom of a lasted or welted shoe. The article or blank to be transferred is engaged by two or more spurs shown 70 separately in Fig. 5 and designated generally by the numeral 6. The operative end of each spur is formed as a chisel point 8 where the sides and bottom of the spur taper into the top surface 10. A stem 12 extends 75 into a hole in the lower end of one of two pivoted levers 14 which have lateral wings 16 (Fig. 3) provided with slots 18, the two sides of each slot being constructed to be drawn together by a screw 20 to clamp the 80 spur. As illustrated, each of the levers 14 carries two spurs 6 which are at a substantial distance apart and the spurs upon the two levers respectively extend in opposite diagonal directions so that as the levers are 85 moved outward while the spurs are being pressed against the upper surface of an article, such as sole 2, they will penetrate such surface in oppositely inclined paths and at a relatively small angle with the surface. 90 The chisel points 8 of the spurs will, therefore, raise, and then extend beneath, small lips or flaps 21 of the sole and secure a substantial hold or grip thereon.

The levers 14, which constitute carriers 95 for the spurs, are pivoted upon a common fulcrum, pin 22, as shown clearly in Fig. 4. Above the fulcrum the levers are provided with projecting pins 23 which confine in place a compression spring 24 interposed between the two levers 14. The tendency of this spring is to cause the spurs to move

60

75

80

85

90

100

toward each other to release an article as shown in Fig. 1. The fulcrum pin 22 is 5
slidable in a slot 26 in a bifurcated end or
head 28 of a rod 34 which thus constitutes
a carrier or slide to support the levers but
is capable of longitudinal movement relative thereto. At the lower end of this head
are formed wedges 30 adapted to engage
beveled surfaces 32 adjacent to the lower
10 ends of levers 14 to force them apart. Bearing
against the upper ends of the levers
and surrounding rod 34 is a washer or
sleeve 36. A spring 38 is interposed between
15 this washer and a collar 40 fixed by
a set screw 42 to the rod 34. The tendency
of the spring 38, therefore, is to move the
head 28 of the slide upward relative to the
levers 14 into contact with the washer 36
20 and also to turn the upper ends of the
levers about the fulcrum pin 22 to bring the
spurs at their minimum distance apart as
shown in Fig. 1. The spring 24 is employed
as already suggested to supplement the
25 spring 38 in moving the levers 14 but the
spring 38 alone may be sufficient. As shown
in Fig. 2, the head 28 is provided with a
lateral lug 44 to which is pivoted at 46 a
latch 48 constructed and arranged to engage
30 a lug 50 projecting laterally from one of
the levers 14. This latch may be released
through an arm 52 and, particularly if the
picker is to be used as an element in a
machine, as already suggested, the arm may
35 be provided with a stop, such as screw 54,
which is arranged to come into engagement
with any suitable abutment 56 as the picker
approaches delivery position whereby the
latch 48 will be released and the springs 38
40 and 24 will force the spurs toward each
other to release the sole.

Applicant has employed mechanism of
this kind for use in transferring sheet filler
material which is of a rather sticky na-
ture with the result that sometimes, when
45 the spurs of a picker such as is shown
in Figs. 2 and 3 are moved toward each
other, the transferred article may still ad-
here to one or more of the spurs. There-
fore, the picker when used for handling
50 articles of this character is preferably pro-
vided with an ejector or stripper which is
conveniently located in the space 60 (Fig.
3) between the lateral wings 16 of levers 14.
This ejector, shown in Fig. 1, comprises a
55 foot 62 having a shank 64 slidably secured
to one of the jaws 14 by screws 66 passing
through slots 68 in the shank 64. A spring
70 contained in a socket in one of the levers
14 and bearing against the shank 64 tends
60 to hold the ejector in projected position
relative to the spurs as shown in Fig. 1.
The shank 64 has a laterally projecting lug
72 with which engages a latch 48', corre-
sponding to the latch 48 already described,
65 by which, when desired, both the ejector is

held in inoperative position and the spurs
are held spread in operative position, the
upper end of the shank being then in en-
gagement with a shoulder 74 on the lever
14.

The operation of the mechanism has al-
ready been indicated but it will now be
briefly described as employed in trans-
ferring articles of sticky material as just
mentioned. However, it will be understood that
70 the ejector 62 need not be used in handling
articles of non-sticking materials in which
case the picker will have the construction
shown in Fig. 2.

The picker may be supported in the hand
of the operator or may be carried upon a
moving part of a machine connected to rod
34, the parts normally occupying the posi-
tion shown in Fig. 1. In using the picker,
it is brought down into engagement with the
80 topmost article 2 in a stack 4. The spurs 6
come into engagement with the upper sur-
face of the article and are forced there-
against with a considerable pressure, de-
termined by the resistance of springs 24
85 and 38, so that they penetrate the surface
of the article. Continued movement of the
rod or slide 34 relative to the levers 14
forces wedges 30 along the inclined sur-
faces 32, spreads the levers and the spurs
90 apart, as shown in Fig. 2, and raises the lips
21, the foot 62 being pressed upward beyond
the plane of the edges 8 of the spurs against
the resistance of spring 70. Finally, latch
48' snaps over the under surface of lug 72
100 so that both the ejector is locked by latch 48'
in inoperative position and also the spurs
are locked in spread or operative position.
The picker is then lifted and with the ar-
105 ticle to be transferred is moved to the de-
livery point. The article having been lo-
cated immediately above the surface to
which it is to be delivered and the stop 54
being somewhat above the abutment 56, at
110 least in the case where the picker is auto-
matically operated or forms an element in
a machine, latch 48' is tripped, either by
hand or by engagement with abutment 56,
allowing springs 24 and 38 to become opera-
115 tive to move the spurs to their innermost
position from beneath the lips 21 while
simultaneously spring 70 throws the foot
62 downward relative to the spurs and pre-
vents the lips 21 from adhering to the spurs.

This complete clearing of the article from
the picker is effectively secured, in the par-
ticular construction illustrated, by reason
of the fact that the ejecting foot acts under
the sudden impulse of the spring 70 at a
central point upon the article relative to the
120 points at which it is engaged by the spurs.
However, if the article is heavy and non ad-
hesive its gravity may be relied on to re-
lease it from the spurs as they spread apart
and a form of construction without a special
130

ejector, such as is shown in Fig. 2, will be suitable.

Having thus indicated the nature and scope of the invention and having described in detail a mechanism in which it is embodied, what I claim as new and desire to secure by Letters Patent of the United States is:

1. Mechanism of the class described comprising, in combination, a plurality of spurs, carriers therefor movable about a common axis to carry the spurs toward or from each other, yielding means continuously tending to move the spurs in one direction relative to each other, and a wedge for moving them positively in the opposite direction.

2. Mechanism of the class described comprising, in combination, a plurality of spurs, carriers therefor movable about a common axis to carry the spurs toward or from each other, a spring and a wedge each acting upon both said carriers respectively to move them in opposite directions.

3. Mechanism of the class described comprising, in combination, a plurality of spurs constructed and arranged to penetrate an article diagonally in opposite directions, carriers therefor movable about a common fulcrum to carry the spurs toward or from each other, a spring constantly tending to move the spurs toward each other, a slide guided by said fulcrum and movable relative to the carriers and also provided with a wedge for separating the spurs to cause them to impale an article presented thereto as the slide is moved longitudinally of the carriers.

4. Mechanism of the class described comprising, in combination, a plurality of devices for engaging an article, a pair of levers carrying said devices, a pin on which the levers are pivoted, a slide having a slot to receive said pin and a wedge to turn the levers about the pin as the slide is moved longitudinally relative thereto, and a spring interposed between a part of the slide and the ends of said levers.

5. In a mechanism for transferring pieces of shoe bottom stock, two pairs of diagonally arranged spurs 6, a pair of pivoted levers 14, carrying the spurs, a pivot pin 22, a slotted slide 28, provided with a wedge 30 for moving said levers in one direction, and a spring 38, constructed and arranged to act upon said slide and levers.

55 6. Mechanism of the class described comprising, in combination, a plurality of spurs, pivoted levers upon which the spurs are carried, yielding means constantly tending to move said spurs in one direction and a movable latch acting upon one of the levers to prevent the action of said yielding means when the latch is in operative position.

7. Mechanism of the class described comprising, in combination, a plurality of devices for engaging an article, a pair of levers

carrying said devices, a slide to which the levers are pivoted with provision for longitudinal bodily movement of the slide relative to the levers, said slide being provided also with a wedge for moving the levers in one direction, a spring constantly tending to move the levers in the opposite direction and a latch on the slide and acting when in operative position to prevent the action of said spring.

8. In a mechanism for transferring pieces of shoe bottom stock, a carrier, a plurality of spurs 6, mounted therein each of which has four faces tapering to a chisel edge 8, the spurs being constructed and arranged in the carrier so that their bottom faces engage the stock at a relatively small angle to the face thereof.

9. Mechanism of the class described comprising, in combination, a plurality of spurs, means for moving the spurs toward and from each other, a foot movable to and from a position in which it projects beyond the ends of the spurs and a movable latch for holding said foot in non-projecting position.

10. Mechanism of the class described comprising, in combination, a plurality of spurs, means for moving the spurs toward and from each other to hold or to release an article, a foot movable to and from a position in which it projects beyond the ends of the spurs and a single movable latch for holding said foot in non-projecting position and the spurs in article-holding position.

11. Mechanism of the class described comprising, in combination, a plurality of devices for engaging an article, a pair of pivoted levers carrying said devices, a slide on which the levers are mounted to move longitudinally of the slide, a foot also movable longitudinally relative to said levers, means constantly tending to move the foot to eject an article held by said devices and a single movable latch for holding the foot in inoperative position and the spurs in operative position.

12. Mechanism for transferring pieces of shoe bottom stock comprising, in combination, a plurality of spurs constructed and arranged to penetrate the stock diagonally in opposite directions, a pair of pivoted levers movable about a common axis to carry said spurs toward or from each other, a foot supported adjacent to said spurs on one of said levers but capable of limited movement relative to the lever, a latch for holding the foot in inoperative position and the spurs in operative position, and means acting automatically upon the release of the latch to move the foot and spurs to eject a piece of stock impaled upon the spurs.

13. Mechanism of the class described comprising, in combination, a plurality of devices for engaging an article, a pair of levers carrying said devices, a support on which

the levers are pivoted, a slide carrying a wedge for turning the levers in one direction, and a spring constantly tending to turn them in the opposite direction.

5 14. Mechanism of the class described comprising, in combination, a plurality of spurs, a pair of pivoted levers carrying said spurs, a foot movable longitudinally relative to said levers to and from a position in which

it projects beyond the ends of the spurs, 10 means constantly tending to move the foot to eject an article engaged by the spurs, and a single movable latch for holding the foot in inoperative position.

In testimony whereof I have signed my 15 name to this specification.

FREDERICK M. FURBER.
